ELECTRIC DRIVE

Rest R. Baker, Pittsburgh, Pa., assignor to Westinghouse Electric Corporation, East Pittsburgh, Pa., a corporation of Pennsylvania

Application October 30, 1946, Serial No. 706,756

8 Claims. (Cl. 318—77)

1

My invention relates to electric drives for creping paper machines.

Such machines have a paper-forming or wet-end section in which the paper stock consolidates and becomes sufficiently self-sustaining to be subjected to a creping device before it enters the drying section of the machinery. The forming section of the machine must be driven at a higher speed than the drying section in order to take care of the shrinkage in length caused by the creping procedure.

It is an object of my invention to provide an electric drive for crepe-forming paper machines in which the operating speeds of the forming and drying sections are automatically and accurately maintained in a given or selected ratio in accordance with a desired percentage of creping, and which permits adjusting the speed of the forming section without affecting the selected percentage of creping.

To this end, and in accordance with a feature of the invention, I provide a generator which is driven by the variable speed motor of the forming section and energizes the drive motor of the drying section, so that the speed of the drying section depends on the speed of the forming section and on the field excitation of the generator. I further provide a control generator, operating at substantially constant speed, for supplying field excitation for the first mentioned generator, and control the field of the control generator by the differential effect of two pilot voltages indicative of the speeds of the two drive motors respectively, these pilot voltages being preferably obtained from two pilot or tachometer generators driven by the two respective motors. In such a system, the first mentioned generator is caused to control the second motor so that the speed of the drying section is maintained at a given percentage below that of the forming section in accordance with the desired percentage of creping; and an adjustable rheostat or the like impedance is preferably arranged in one of the field circuits of the control generator to permit selecting the percentage of creping.

These and other objects and features of my invention will be apparent from the following description of the embodiment shown in the drawing.

The drawing represents schematically some parts of a creping paper machine in conjunction with the circuit diagram of an appertaining electric drive according to the invention.

In the machinery illustrated on the drawing, a group of pulp nozzles 1 deposits the paper stock 55

2

in wet condition on an endless pulp screen 3 supported by rollers 4 and 5. Thence the stock enters between two endless felts 6 and 7. Felt 6 is supported and guided by a number of rollers such as those denoted by 8, 9 and 10, and felt 7 is similarly supported and guided by rollers such as those denoted by 11 and 12. The rollers 9 and 11 form together a roll press. As the stock travels from the pulp screen to the roller 10, sufficient liquid is removed therefrom to render the stock nearly self-supporting for the subsequent creping and drying operations. The stock then passes onto a dryer roll 13 which forms the last unit of the just described wet-end or forming section of the machine.

The individual driven devices of the forming section are geared to a line shaft 15 by means of suitable transmissions here schematically represented by a gear box 16 for driving the pulp screen roll 5, a gear box 17 for driving the bottom roll 11 of the roll press, a gear box 18 for driving the end roll 10 of the felt 6, and a gear box 19 in driving connection with the dryer roll 13. The line shaft 15 is driven through the gear box 16 from a reduction gear 20 whose input shaft is coupled to an electric motor M1.

After the paper stock has passed over most of the periphery of the dryer roll 13, it is subjected to a crepe doctor blade 23 so that the paper deflected from the roll 13 has the desired creped consistency. A second doctor blade 24 contacting the dryer roll 13 serves to clean it from residual amounts of stock.

The creped material passes into the drying section which includes a crepe set dryer 25, a group of drying rolls 26, 27 and 28, and a calender represented by the two rolls 29 and 30. After leaving the calender, the finished material is wound onto a roll 31. The driven devices of the drying section are geared to a line shaft 32 by transmissions which are schematically represented by gear boxes 33, 34, 35 and 36. The line shaft 32 or the gear box 36 is driven through a reduction gear 37 from another electric motor M2.

It will be understood that the above described machinery is represented merely for the purpose of explanation and exemplification, and that its specific design and arrangement is not a feature of the invention proper. The invention as such resides in the electric equipment to be described presently in connection with the two above-mentioned drive motors M1 and M2 of the crepe-forming paper machinery.

Both motors M1 and M2 are adjustable-speed direct-current motors and receive energization

from respective generators. The armature of motor M1 is denoted by 41 and an appertaining field winding by 42. Armature 41 is connected to the armature 43 of a generator G1 which is driven at substantially constant speed by an auxiliary motor 44 and generates the motor load voltage under control by a separately excited field winding 45.

The field windings 42 and 45 are excited from direct current mains X and Y. These mains are energized by an exciter generator EX whose armature 46 is driven at substantially constant speed and to this end preferably mounted on the shaft 47 of generator G1. The exciter EX has a series field winding 48 and a shunt field winding 49, and supplies mains X and Y with substantially constant voltage. A field rheostat 51 is series-connected with motor field winding 42 between mains X and Y, and another field rheostat 52 is series-connected with generator field winding 45 between the mains. The two field rheostats 51 and 52 permit adjusting the speed of motor M1 to any desired value within the available range of speeds, for instance, between 90 and 330 rotations per minute. As customary, the sliders of the two rheostats may be ganged together in order to facilitate setting the adjustable voltage drive to the desired speed value.

The adjustable voltage for the drive motor M2 of the drying section is provided by another generator G2 whose armature 53 is mounted on or geared to the shaft 54 of drive motor M1. The voltage generated by armature 53 is controlled by two field windings 55 and 56. Field winding 55 receives constant excitation from mains X and Y through an adjusting rheostat 57, while field winding 56 is excited by variable voltage from a control generator CG. The two field windings 55 and 56 operate cumulatively. That is, the constant excitation of field winding 55 is so adjusted that the minimum voltage generated in armature 53 is somewhat below the value corresponding to the minimum speed of motor M2, and the variable excitation applied to field winding 56 takes care of varying the voltage and speed within the required range.

The control generator CG has its armature 58 driven at substantially constant speed. To this end the armature, as illustrated, may be mounted on or connected to the shaft 47 of generator G1. Generator CG has three field windings 59, 60 and 61. Winding 59, here shown as a series winding, is self-excited, while the windings 60 and 61 receive separate excitation of opposing directions, so that the field effects of windings 60 and 61 are differential and balanceable with respect to each other. The control generator CG is preferably of the amplifying type. In the illustrated example, the amplifying performance is obtained in the following manner. The circuit of the self-excited field winding 59 is so "tuned" that the resistance line of this circuit coincides approximately with the no-load saturation characteristic of the control generator. As a result, the self-excitation of the machine is sufficient to generate the desired output voltage and to maintain this voltage at any point along the straight portion of the voltage characteristic. Consequently, the resultant effect of the control field windings 60 and 61 is merely required to supply the impulse necessary for shifting the operating point of the machine along the straight portion of the characteristics. Thus, a very small amount of differential excitation to be supplied by field windings 60 and 61 suffices to change the output

voltage of generator CG a proportionally large amount. The circuit devices for controlling the differential excitation of field windings 60 and 61 will be described in a later place.

5 The armature 53 of generator G2 is connected through a switch or contactor 62 to the armature 63 of the drying section drive motor M2. The motor M2 has a field winding 64 excited from mains X and Y through a calibrating rheostat 65. The adjustment of this rheostat is normally fixed during the operation of the system so that the speed of motor M2 depends on the voltage generated in armature 53 of generator G2. This voltage, as will be understood from the foregoing, depends on two controlling factors, namely, on the speed of the drive motor M1 and on the field excitation of generator G2. Since the excitation of generator field winding 55 is normally constant during the operation of the machine, the second factor for determining the speed of motor M2 is represented by the variable excitation of field winding 56 which, as explained above, depends only on the differential effect of field windings 60 and 61 in the control generator CG.

Field winding 60 is connected to the armature 67 of a tachometer or pilot generator P1. Armature 67 is mounted on or geared to the shaft 54 of motor M1. The appertaining field winding 68 is excited by constant voltage so that the pilot voltage produced by pilot generator P1 and imposed on the field winding 60 is proportional to the operating speed of motor M1, and hence of the forming section of the machinery.

35 Field winding 61 of generator CG is connected to the armature 69 of another tachometer or pilot generator P2 whose field winding is denoted by 70. The armature 69 is mounted on or geared to the shaft of drive motor M2. Since field winding 70 receives constant excitation, the voltage of generator P2 changes in proportion to speed variations of motor M2, and the field winding 61 in generator CG is excited accordingly. The field windings 68 and 70 of respective pilot generators P1 and P2 are preferably series-connected to each other between the mains X and Y under inclusion of a series rheostat 71. The application of such a series connection for the pilot generator field windings has the advantage of compensating the control equipment for slight temperature variations and for variations in exciter voltage because any such variations will affect the output of both pilot excitors to a substantially equal extent, and, since these two excitors feed two differentially acting fields of the control generator, the variations have substantially no disturbing effect on the control performance. A rheostat 72 is disposed in the circuit of field winding 61. This rheostat permits adjusting the excitation of field winding 61 as regards its proportion to the voltage generated in the pilot exciter P2. In this manner the two field windings 60 and 61 can be made to balance each other at a desired speed differential of the motors M1 and M2 in accordance with the intended percentage of creping.

Reviewing the performance of the machinery and the control system as a whole, it will be understood that in order to secure the desired degree or percentage of creping and a satisfactory constancy of the creped material, the speed of the drying section, driven by motor M2, must be maintained a given percentage below the speed of the forming section driven by motor M1. For instance, if a creping of 30% is required, and as-

suming a speed range of motor M1 between 90 and 330 rotations per minute, the speed of motor M2 must be accordingly maintained at a correspondingly lower speed within the range of 63 to 230 rotations per minute. When, during the operation of the machine, the speed of motor M1 is varied within the just-mentioned range, the dependent speed of motor M2 must maintain the same speed differential and thus vary automatically in proportion to the speed change of motor M1, and this performance should obtain irrespective of slight fluctuations in speed or changes in load. Assuming the motor M1 to be operating at a given speed determined by the selective setting of rheostats 51 and 52, and with switch or contactor 62 closed, the voltage generated by generator G2 changes substantially in proportion to the speed of motor M1. If motor M2 is running correctly at the desired speed, the excitation of field windings 60 and 61 is balanced, and the resultant field excitation of generator G2 constant. If motor M2 were running at a lower speed than required, the voltage impressed on field winding 61 would drop so that the field of winding 60 becomes preponderant and causes the voltage of generator G2 to increase. This, in turn, increases the field excitation of generator G2 and causes the motor M2 to increase its speed to the desired value. Conversely, at an excessive speed of motor M2 the effect of field winding 61 would dominate over the countereffect of field winding 60 and then cause the generator G2 to reduce the excitation of field winding 60, thus causing the generator G2 to impress low voltage on motor M2. Consequently, the system operates to maintain the motor M2 accurately at a given speed differential relative to motor M1. Since this differential depends on the balanced condition of windings 60 and 61, a change in the adjustment of rheostat 72 has the effect of increasing or reducing the differential and hence the percentage of creping.

It will be understood by those skilled in the art that electric drive systems according to the invention can be altered and modified as regards various details and with respect to specific circuit connections without departing from the principles of the invention, and within its essential features as set forth in the claims attached hereto.

I claim as my invention:

1. An electric drive for a creping paper machine having a paper forming section and a drying section, comprising a first motor for the forming section, a generator having an armature mechanically connected with said first motor to be driven thereby and having a field winding, a second motor for the drying section electrically connected to said generator armature to be energized therefrom in dependence upon the speed of said first motor and the excitation of said field winding, two pilot generators mechanically connected to said first and second motors to generate two pilot voltages indicative of the speeds of said respective motors, a control generator operable at substantially constant speed and having an armature electrically connected to said field winding for controlling said excitation and having field means connected to said two pilot generators to be energized in dependence upon the differential value of said pilot voltages in order to cause said first generator to operate said second motor substantially at a speed a given percentage below that of said first motor in accordance with a desired percentage of creping.

2. An electric drive for a creping paper machine

having a paper forming section and a crepe drying section, comprising a first motor for the forming section, a generator having an armature mechanically connected with said first motor to be driven thereby and having a field winding, a second motor for the drying section electrically connected to said generator armature to be energized therefrom in dependence upon the speed of said first motor and the excitation of said field winding, two pilot generators mechanically connected to said first and second motors to generate two pilot voltages indicative of the speeds of said respective motors, a control generator operable at substantially constant speed and having an armature electrically connected to said field winding for providing said excitation and two mutually balanceable control field windings for differentially controlling said excitation, said control field windings being connected to said pilot generators respectively to be energized by said respective pilot voltages in order to cause said first generator to operate said second motor substantially at a speed a given percentage below that of said first motor, and adjustable rheostat means disposed between one of said pilot generators and the appertaining control field winding to permit adjusting said percentage in accordance with a desired percentage of creping.

3. An electric drive for a creping paper machine having a paper forming section and a crepe drying section, comprising a first motor for the forming section, a generator having an armature mechanically connected with said first motor to be driven thereby and having a field winding, a second motor for the drying section electrically connected to said generator armature to be energized therefrom in dependence upon the speed of said first motor and the excitation of said field winding, two pilot generators having respective armatures mechanically connected to said first and second motors and having each a field winding for providing two pilot voltages indicative of the speeds of said respective motors, means disposed for providing a substantially constant voltage and connected to said two field windings of said respective pilot generators, said latter windings being arranged in series relation to each other, a control generator operable at substantially constant speed and having an armature electrically connected to said field winding for controlling said excitation and having field means connected to said two pilot generators to be energized in dependence upon the differential value of said pilot voltages in order to cause said first generator to operate said second motor substantially at a speed a given percentage below that of said first motor in accordance with a desired percentage of creping.

4. An electric drive for a creping paper machine having a paper forming section and a crepe drying section, comprising a first motor for the forming section, a generator having an armature mechanically connected with said first motor to be driven thereby and having a field winding, a second motor for the drying section electrically connected to said generator armature to be energized therefrom in dependence upon the speed of said first motor and the excitation of said field winding, two pilot generators having respective armatures mechanically connected to said first and second motors and having each a field winding for providing two pilot voltages indicative of the speeds of said respective motors, means disposed for providing a substantially constant voltage and connected to said two field windings of

said respective pilot generators, said latter windings being arranged in series relation to each other, a control generator operable at substantially constant speed and having an armature electrically connected to said field winding for providing said excitation and two mutually balanceable control field windings for differentially controlling said excitation, said control field windings being connected to said pilot generators respectively to be energized by said respective pilot voltages in order to cause said first generator to operate said second motor substantially at a speed a given percentage below that of said first motor, and adjustable rheostat means disposed between the pilot generator appertaining to said second motor and the appertaining control field winding of said control generator to permit selecting said percentage in accordance with a desired percentage of creping.

5. An electric drive for a creping paper machine having a paper forming section and a crepe drying section, comprising first and second direct-current motors for driving the forming and drying sections respectively, a main generator having an armature operable at substantially constant speed and electrically connected to said first motor to supply adjustable voltage thereto, another generator having an armature mechanically connected to said first motor and electrically connected to said second motor and having a field winding, two pilot generators mechanically connected to said first and second motors to generate two pilot voltages indicative of the speeds of said respective motors, a control generator having an armature mechanically connected to that of said main generator and electrically connected to said field winding, two mutually differential control field windings disposed on said control generator and connected to said respective pilot generators to control said control generator in dependence upon the differential value of said pilot voltages in order to cause said other generator to operate said second motor substantially at a speed a given percentage below that of said first motor in accordance with a desired percentage of creping.

6. An electric drive for a creping paper machine having a paper forming section and a crepe drying section, comprising first and second direct-current motors for driving the forming and drying sections respectively, a main generator having an armature operable at substantially constant speed and electrically connected to said first motor to supply adjustable voltage thereto, another generator having an armature mechanically connected to said first motor and electrically connected to said second motor and having a field winding, speed-responsive measuring means associated with said respective motors for providing two pilot voltages indicative of the speeds of said respective motors, a control generator operable at substantially constant speed and having an armature connected to said field winding for providing variable excitation therefor and having field means connected to said speed responsive means so as to control said excitation in dependence upon the differential value of said pilot voltages for causing said other generator to operate said second motor substantially at a speed a given

percentage below that of said first motor in accordance with a desired percentage of creping.

7. An electric drive for a creping paper machine having a paper forming section and a crepe drying section, comprising first and second direct-current motors for driving the forming and drying sections respectively, a main generator having an armature operable at substantially constant speed and electrically connected to said first motor to supply adjustable voltage thereto, another generator having an armature mechanically connected to said first motor and electrically connected to said second motor and having a field winding, two pilot generators mechanically connected to said first and second motors to generate two pilot voltages indicative of the speeds of said respective motors, said pilot generators having respective field coils arranged in series relation to each other, a constant voltage exciter mechanically connected with said armature of said main generator and electrically connected to said series arrangement to provide excitation for said pilot generators, said exciter being also electrically connected to said main and other generators and said two motors to provide normally constant field excitation therefor, a control generator having an armature mechanically connected to that of said main generator and electrically connected to said field winding, two mutually differential control field windings disposed on said control generator and connected to said respective pilot generators to control said control generator in dependence upon the differential value of said pilot voltages in order to cause said other generator to operate said second motor substantially at a speed a given percentage below that of said first motor in accordance with a desired percentage of creping.

8. An electric drive for a creping paper machine having a paper forming section and a crepe drying section, comprising first and second direct-current motors for driving the forming and drying sections respectively, a main generator having an armature operable at substantially constant speed and electrically connected to said first motor to supply adjustable voltage thereto, another generator having an armature mechanically connected to said first motor and electrically connected to said second motor and having a field winding, two pilot generators mechanically connected to said first and second motors to generate two pilot voltages indicative of the speeds of said respective motors, a control generator having an armature operable at substantially constant speed and connected to said field winding to provide excitation therefor, said control generator having two opposingly acting control field windings connected to said pilot generators respectively for controlling said excitation in order to cause said other generator to operate said second motor substantially at a speed a given percentage below that of said first motor, and adjustable rheostat means disposed between said pilot generator appertaining to said second motor and the appertaining control field winding of said control generator to permit adjusting said percentage in accordance with a desired percentage of creping.

REST R. BAKER.
